CLAIM

The ornamental design for a waste bag dispenser as shown and described.

DESCRIPTION

FIG. 1 is a top, front and right perspective view of a waste bag dispenser showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof; and,

FIG. 8 is a bottom, rear and left perspective view.

The evenly broken lines illustrate portions of the waste bag dispenser that form no part of the claimed design.
